INVENTOR
Irving C. Hicks
BY *Arthur Brown*
ATTORNEY

UNITED STATES PATENT OFFICE

IRVING C. HICKS, OF TOPEKA, KANSAS, ASSIGNOR TO THE TIMKEN ROLLER BEARING COMPANY, OF CANTON, OHIO, A CORPORATION OF OHIO

CAR TRUCK

Application filed October 28, 1927. Serial No. 229,448.

My invention relates to car trucks, and more particularly to side frames of car trucks, the principal objects of the invention being to improve the means of supporting a car 5 axle in side frames, to provide more efficient bearing elements for the axle, and to increase the durability of the frames.

In accomplishing these and other objects of the invention I have provided improved 10 details of structure, the preferred forms of which are illustrated in the accompanying drawings, wherein:

Fig. 1 is a perspective view of a car truck provided with improved side frames and 15 journaling elements embodying my invention, part of a journal housing being broken away the better to illustrate journaling elements.

Fig. 2 is a vertical transverse section of the 20 journal housing member and journaling elements associated with a car wheel and axle.

Fig. 3 is a detail perspective view of a housing member and a portion of a side frame with which it is integral.

Fig. 4 is a similar view of the opposite side 25 of the housing member.

Referring in detail to the drawings:

1 designates the wheels of a railway car, having axles 2 provided with journals 3, and 4 designates similar side frames positioned 30 on opposite sides of a set of wheels having openings 5 to receive a transverse element 6 and springs 7 for support of the transverse, and conventional truck parts by the side frames. The side frames are supported by 35 the wheel axles, and similar housing members 8 are provided on each end of each frame, and integral with the frames, to contain the journaling elements, a side frame being preferably cast to provide the single integral element including the housings.

One of said housing members comprises a circular box extending from a reduced end portion 9 of the frame, the top of the housing being substantially aligned with the upper 45 surface of said reduced end and the bottom of the housing depending below the lower surface of said end, whereby the transverse axis of the housing is positioned in the longitudinal axis of the frame. The housing is provided with an internal annular inside flange 50

10 to retain a journal casing 11 provided with an annular grease retaining flange 12 engaged with the shoulder 13 of the journal of the axle. A cover plate 14 for mounting over the outer end of the journal in the housing 55 opening is provided with a flange 15 connected with the outer edge of the journal casing by bolts 16, and with a shoulder 17 for engaging the inner periphery of the casing. A flanged annulus 18 constituting a keeper ring 60 bolted to the housing on the margin of the housing opening shelters the journal casing and the attaching flange of the cover.

Beveled outer races 19 and 20 are press-fitted within the journal casing, and these are 65 adapted to receive two spaced sets of tapered roller bearings 21 and 22, which operate effectively on a beveled inner race 23 having recesses 24 and 25 to receive the roller bearings, the ends of the recesses providing shoulders to retain the bearings, and the race being engaged with the axle journal; the larger ends of the spaced bearings being adjacent. The sets of races are suitably oppositely disposed for the bearings which roll between 70 them. The interior outer race is retained in position by engagement of its portion of larger diameter with the grease flange of the journal casing, and the exterior outer race is retained by the shoulder 17 of the cover, the 75 two outer races being spaced. The inner race is retained interiorly by the shoulder of the journal and exteriorly by a washer-like element 26, a nut 27 threaded on the journal bearing against the washer and retained from 80 rotational displacement by means such as a cotter 28. The outer races are spaced to provide an oil channel 29, and an oil inlet 30 is provided in the cover.

The elements having been provided and 85 assembled as described, the weight of the axle and load is distributed over the relatively extensive surfaces of the several rollers that may be in the upper arc at the moment of carrying. Rotation of the wheels causes 90 the roller bearings to roll in the races.

When the wheels are rotated, a relatively 95 large movable contact surface is available and utilized, reducing wear and pressure on any one point, and increasing the efficiency 100

of oil films. The oppositely disposed cones further enhance the efficiency of the journaling elements by receiving and sustaining the shifts of load from tilting of the axle or other causes, providing adequate bearing surfaces and effectively operating bearings for the temporary thrusts or impacts, or for stress coincidental with a vertical burden.

What I claim and desire to secure by Letters Patent is:

- 10 1. In combination with a car truck and the wheel journals thereof, a side frame comprising a cast element having ring-shaped journal housings integral therewith, a journal casing in each ring-shaped housing, roller bearing sets supported between the wheel journal and the journal casing, a cover plate fixed to the journal casing, and a keeper ring attached to the ring-shaped housing to retain the journal casing.
- 15 2. In combination with a car truck and the wheel journals thereof, a side frame comprising a cast element having journal housings integral therewith, each housing having an interior annular casing-retaining flange, a journal casing in the housing, tapered roller bearing sets supported between the wheel journal and the journal casing having outer and inner races, a cover plate fixed to the journal casing having a shoulder bearing against one of said outer races, and a keeper ring attached to the housing to retain the journal casing.
- 20 3. In combination with a car truck and the wheel journals thereof, a side frame having ring shaped journal housings integral therewith, and having cylindrical bores, a journal casing in each ring-shaped housing having a laterally curved periphery to provide rocking contact with the journal housings, and keeper rings for limiting longitudinal movement of the journal casing in the journal housings.
- 25 4. In combination with a car truck and the wheel journals thereof, a side frame having integral ring-shaped journal housings, a journal casing in each ring-shaped housing having rocking contact with relation to the journal housings, roller bearing sets supported between the wheel journal and the journal casing, a cover plate fixed to the journal casing to retain the bearing sets and means for limiting longitudinal movement of the journal casings in the journal housings,
- 30 55 In testimony whereof I affix my signature.
IRVING C. HICKS.
